UNITED STATES PATENT OFFICE.

WALTER H. HOLT, OF CRAFTON, PENNSYLVANIA, ASSIGNEE TO PRERESSED STEEL CAR COMPANY, OF PITTSBURGH, PENNSYLVANIA, A CORPORATION OF NEW JERSEY.

MOLDING FLASK.

Application filed August 12, 1924. Serial No. 721,761.

To all whom it may concern:

Be it known that I, WALTER H. HOLT, a citizen of the United States, residing in Crafton, in the county of Allegheny and State of Pennsylvania, have invented certain new and useful Improvements in Molding Flasks, of which the following is a specification.

This invention relates to the art of molding and has for an object improvements in the construction of the molder's flask or receptacle which are simple and efficient.

Another object of the invention is to provide a molder's flask with adjustable means for accommodating patterns of varying heights and configurations and for the retention of the molded sand in the flask after the pattern has been withdrawn.

These and other objects will be apparent from the following description.

Referring to the drawings in which like reference characters refer to like parts, Fig. 1 is a plan view of a molding flask embodying the invention and Figs. 2 and 3 are sectional views of the same taken on the lines 2-2 and 3-3 respectively of Fig. 1.

Referring now in detail to the drawings, the reference character 1 indicates the frame of the cope of a molding flask which comprises sides 2 and ends 3 which may be made of wood or metal suitably connected together. Between the sides 2 transverse members 4 are provided, each of which comprise a bar 5 having plates 6 mounted thereon. At each of its ends this bar is provided with a flange 7, preferably having projections 8 which extend through openings formed in the sides 2. These bars are held in their proper positions by means of wedge members 9 which engage the projections 8 within the openings formed therein and also engage the sides 2. Each of the bars 5 is provided with a plurality of projections 10 which are suitably spaced apart longitudinally of the bar. Each of the plates 6 are provided with a plurality of sets of openings 12 the openings of each set being spaced longitudinally of the plate the same distance apart as the projections 10 of the bars 5 are spaced. The sets of openings are spaced apart transversely of the plate any desired distance. When the plates 6 are mounted on one of the bars 5 the projections 10 extend through one of the sets

of openings in each plate and the plate and bars are secured together by means of wedge members 13 which pass through slotted openings formed in the projections 10 such members 13 engaging the projections within the openings and on either side of the projections engaging the plates 6.

As shown in full lines in the drawing, the plates 6 are in their lowermost operative positions in which positions the projections 10 extend through the first set of openings 12 in the plates 6. As shown in dot and dash lines in Fig. 2 the plates 6 are in their uppermost positions and when in such positions the projections 10 extend through the last set of openings 12. It will be noted that the plates may be adjusted vertically to any desired height and independently of each other, also that by the removal of one of the plates 6, the other plate 6 may be adjusted transversely to any desired position, as well as vertically.

It will be apparent to those skilled in the art to which this invention appertains that changes may be made in the manner of adjusting the plates 6 on the bar 5, without departing from the spirit and scope of the appended claims.

Claims:

Having thus described the invention, what I claim as new and desire to secure by Letters Patent is:

1. In a molding flask having sides, a bar extending between and connected with said sides, and a plate mounted on said bar adapted to be adjusted relative to said bar.
2. In a molding flask having sides, a bar extending between and connected with said sides and plates mounted on said bar adapted to be adjusted vertically relative to said bar.
3. In a molding flask having a bar secured therein, and a plate mounted on said bar and adjustable vertically and transversely relative thereto.
4. In a molding flask having a bar secured therein, and a plurality of plates mounted on said bar, said plates being adjustable relative to said bar and to each other.
5. In a molding flask, a stationary bar secured to said flask, a single set of projections on said bar, and a plate adjustable relative to said bar and removably mounted on said projections, said plate having a plurality of

sets of openings adapted to receive said projections.

6. In a molding flask, a stationary bar, projections on said bar, a plate adjustable relative to said bar, said plate having a plurality of sets of openings formed therein through which said projections are adapted to extend to support said plate in its adjusted position, and means for removably se-
10 curing said plate to said bar.

7. In a molding flask, a transverse member for said flask, said member comprising a

bar, and a plate adjustable relative to said bar.

8. In a molding flask, a bar extending 15 across said flask, projections on said bar, a perforated plate, the perforations in said plate being arranged in sets one above the other, any one of said sets of perforations being adapted to receive said projections to 20 adjust the position of said plate.

In testimony whereof, I affix my signature.

WALTER H. HOLT.
